UNITED STATES PATENT OFFICE.

SUSAN I. ODLIN, OF DAYTON, OHIO.

HAND LOOM.

Application filed August 10, 1927. Serial No. 212,097.

This invention relates to a new and useful hand loom expressly designed for school room use, and constructed with a view toward simplifying and systemizing industrial work.

- My principal aim is to generally improve upon devices of this class by providing one which is characterized by such indispensable features as compactness and convenience of arrangement of parts, adjustability, simplicity, and durability and strength, such as is essential in an article of this kind, which is subjected to such continuous and unreliable handling.
- 15 An equally important aim is to provide a structure of this class, which facilitates manipulation by unskilled hands, in weaving various domestic articles such as rugs, hammocks, belts, bands, etc.
- 20 In addition, I propose a structure of this nature which is provided with means for retaining in position a drawn plan to function as a guide in weaving artistic and ornamental designs in the finished product.
- 25 Other structural features and accompanying advantages will be clear from the following description and drawings.

In the drawings:—

Figure 1 is a perspective view of a loom constructed in accordance with the present invention, observing one side of the same.

Fig. 2 is likewise a perspective view looking at the opposite side of the structure.

Fig. 3 is a fragmentary detail view showing a slightly modified feature of the invention.

In carrying out the invention, I employ a novel frame. This embodies a pair of spaced parallel side bars 4, each bar being composed of a pair of substantially duplicate bar sections 5 attached together, through the medium of substantially rectangular eyes 6. Incidentally one of the eyes carries a set screw 7. Thus, the bar sections are extensively connected together.

The outer end portions of the bars are directed at right angles as at 8 and fastened to the ends of a pair of cross members 9. Attention is here directed to longitudinally spaced notches 10 forming keeper seats for elongated longitudinally shiftable loops 11. It will be noted that each loop is provided at one end with a set screw 12.

Considering further the construction of the end members, 9 it will be observed that the outer edges of these are provided with a

multiplicity of slots 13 for reception of the warp strands 14. In connection with the slots, it should be noted that they are graduated in length, decreasing gradually toward 60 the center on an arcuate line. Obviously, this arrangement of slots is for the making of hammocks. Attention might be directed to the fact that a multiplicity of strands 14 as shown in dotted lines and arranged on 65 the frame for the making of a hammock, the contracted end portions being connected to rings 15 and tied together as at 16 on one side of the frame as represented in Fig. 2.

As before indicated, a plan or guide is 70 employed for the making of designs, and this comprises a sheet of paper or other similar material 17 which is stretched tautly across the back of the frame and has its ends clamped under the bar loops 11 as indicated at 18 in Fig. 2. A suitable design 19 is formed on the top of the sheet to provide an outline for weaving of the design by the weft threads.

Attention is invited to the fact that the 80 aforesaid elongated loops 11 have a double function. First, they serve to clamp the sheet of paper 17 in place, as represented in Fig. 2. Then, they can be shifted outwardly and seated in the outer keeper seats 85 in which position, the outer edges provide a straight shoulder over which the warp strands are trained. In other words, the end members 9 are particularly notched for the making of hammocks. However, where 90 it is desired to have all of the warp threads terminate in an even line, it is obvious that this arrangement of slots would not do, and therefore the elongated loops 11 are shifted outwardly and aline with the short notches 95 at the center. Then the loops constitute backing members, over which the warp threads are drawn for straight work such as rugs, bands, etc.

I also wish to direct attention to the fact 100 that in Fig. 3, I have shown the end members provided with tongues 20 which are fastened in grooves in enlarged heads 21 on the bar sections 5. In other words instead of fastening the bars by screws to the cross 105 pieces or members 9, they may be fastened in this particular manner if occasion dictates.

In conclusion, it is to be stated, that I 110 have evolved and produced a readily portable and easily handled loom for school room and home purposes, which is individ-

ualized by durability of construction, simplicity, adjustability, and compactness and convenience, making for easily storing and handling in school-rooms.

5 It is believed that these advantages, as well as others, have been made apparent from the foregoing description and drawings. Therefore, a more lengthy description is thought unnecessary.

10 Minor changes in shape, size, and rearrangement of parts coming within the field of invention claimed, may be resorted to if desired.

Having thus described my invention, 15 what I claim as new is:—

1. As a new product of manufacture, a hand loom comprising a frame embodying longitudinally extensible side bars, end members connected with the end portions of said side bars, said end members being provided on their outer edges with a multiplicity of 20 slots for reception of warp strands, said slots being graduated in length from the

center of the end members toward the ends of the latter, thus permitting arrangement 25 of the strands in substantially arcuate lines for the making of hammocks, together with longitudinally shiftable clamping loops embracing the end portions of the side bars, and said end members.

2. In a hand loom of the class described, a pair of end members provided with slots to accommodate warp strands, a pair of duplicate side bars composed of adjustably connected sections, fastened at their ends to said end members, the end portions of the side bars provided with longitudinally spaced notches forming keeper seats, and a pair of elongated loop members embracing the end portions of said side bars, and said end members, said loops being cooperable with said keeper seats, and retaining screws carried by said loops.

30 In testimony whereof I affix my signature.

SUSAN I. ODLIN.
